UNITED STATES PATENT OFFICE.

OTTO E. FICK, OF MILWAUKEE, WISCONSIN, ASSIGNOR TO THE MILWAUKEE LITHOGRAPHIC AND ENGRAVING COMPANY, OF SAME PLACE.

DESIGN FOR A BLANK FOR IMITATION MUGS.

SPECIFICATION forming part of Design No. 34,063, dated February 12, 1901.

Application filed January 4, 1900. Serial No. 395. Term of patent 7 years.

To all whom it may concern:

Be it known that I, OTTO E. FICK, a citizen of the United States, residing at Milwaukee, in the county of Milwaukee and State of Wisconsin, have invented and produced a new and original Design for a Blank for Imitation Mugs, of which the following is a specification, reference being had to the accompanying drawing, forming a part thereof.

This design relates to devices made out of cardboard or other flexible material for advertising or other purposes.

As shown in the drawing, the leading or material feature of the design consists in the shape or contour of the blank for an imitation mug or cup. The upper and lower edges of the blank are cut or formed on arcs of concentric circles, and the ends are formed approximately on radial lines diverging downwardly toward the lower arc, which represents the base of the mug or cup. At one end the blank is cut or formed to represent a handle 1. At the other end it is formed with a

tongue or ear 3 on the end with the handle 25 and has attached to its upper curved edge, representing the top of the mug or cup, a flap 4, representing a hinged cover or lid. Near the end opposite the handle the blank has a radial slit 5, corresponding in length and position with the handle, and near the opposite end it has radial slits 6 6, corresponding in length and position with the tongues or ears 2 2. The part 7, severed from the handle 1 along its inner margin, is left attached as a 35 flap to the blank on the dotted line 8.

Having thus described my invention, what I claim as new, and desire to secure by Letters Patent, is—

The design for a blank for imitation mugs 40 or cups, substantially as herein shown and described.

In witness whereof I hereto affix my signature in presence of two witnesses.

OTTO E. FICK.
